UNITED STATES PATENT OFFICE

127,926

DESIGN FOR A FABRIC PATCH MENDING DEVICE

Edward N. Simmons, Chicago, Ill.

Application June 17, 1940, Serial No. 93,049

Term of patent 7 years

To all whom it may concern:

Be it known that I, Edward N. Simmons, a citizen of the United States and a resident of Chicago, county of Cook, and State of Illinois, have invented a new, original, and ornamental Design for a Fabric Patch Mending Device, of which the following is a specification, reference being had to the accompanying drawing, forming part thereof.

In the drawing:

I claim:

The ornamental design for a fabric patch mending device, substantially as shown.

EDWARD N. SIMMONS.
